UNITED STATES PATENT OFFICE.

FREDERICK W. SPERR, JR., OF OAKMONT, PENNSYLVANIA, AND A. ALLISON KOHR, OF NEWARK, NEW JERSEY, ASSIGNEES TO THE KOPPERS COMPANY, OF PITTSBURGH, PENNSYLVANIA, A CORPORATION OF PENNSYLVANIA.

APPARATUS FOR DETERMINING SOLUBLE GAS CONSTITUENTS.

1,316,692.

Specification of Letters Patent. Patented Sept. 23, 1919.

Application filed December 3, 1918. Serial No. 235,100.

To all whom it may concern:

Be it known that we, FREDERICK W. SPERR, Jr., and A. ALLISON KOHR, both citizens of the United States, residing, respectively, at 5 Oakmont, Allegheny county, Pennsylvania, and Newark, in the county of Essex and State of New Jersey, have invented a new and useful Improvement in Apparatus for Determining Soluble Gas Constituents, of 10 which the following is a full, clear, and exact description, reference being had to the accompanying drawing, forming part of this specification, in which—

Figure 1 is a sectional plan view of one 15 form of apparatus embodying our invention, and

Fig. 2 is a vertical section of the same.

Our invention has relation to apparatus particularly designed for the determination 20 of the amount of benzol in coke oven or illuminating gases, but which may be used for the determination of any constituent of a gas which is soluble in a liquid absorbing medium.

25 One object of our invention is to provide an apparatus of this character having a plurality of absorbing coils placed in separate vessels and so arranged that the last traces of the absorbable vapors may be removed 30 from the gas. A further object is to arrange the coil containing vessels in such a manner that both of them may be simultaneously and quickly drained, without the necessity for taking apart various connections for this purpose. Our invention also 35 provides an apparatus of this character in which the parts may be quickly assembled and removed; and which can be easily cleaned and which is a compact apparatus 40 of high efficiency.

The nature of our invention will be best 45 understood by reference to the accompanying drawing in which we have shown a preferred embodiment thereof as heretofore actually constructed, and which will now be described, it being premised, however, that various changes can be made in the details of construction, arrangement and combination 50 of the several parts without departing from the spirit and scope of our invention, as defined in the appended claims.

In this drawing the apparatus is shown as consisting of two concentric vessels 2 and 3, each of which contains an absorbing coil,

designated at 4 and 5, respectively. The 55 outer vessel 3 is provided with a surrounding water or oil jacket 6 which is shown as being supported upon a suitable frame or stand 7. The upper edge of the inner vessel 2 is flanged outwardly, as indicated at 2^a, 60 and this flanged edge is secured to the flanged upper edge 3^a of the outer vessel and also to a cover plate 7^a by suitable means such as screws 8. The plate is extended sufficiently to also serve as a cover for the jacket 65 forming vessel 6. This jacket is used whenever it is necessary to maintain the temperature in the absorbing vessels at a point different from the temperature of the atmosphere. The vessels 2 and 3 are preferably 70 constructed of sheet copper while the jacket may be made of galvanized steel or other suitable material.

The inner vessel 2 has an outlet pipe 9 at 75 its lower end which is controlled by a valve 9^a mounted on a stem which passes upwardly through a suitable stuffing box 10 secured in the cover plate 7^a, and provided at its upper end with a suitable actuating means such as the handle 11. The outer 80 vessel 3 has an outlet pipe 12 which extends downwardly through the bottom of the water jacket and is provided with a controlling valve 13. The outlet pipe 12 has a threaded joint at 14 to permit the removal of the gas 85 absorbing chambers from the water jacket when the screws holding the cover plate to the jacket are removed. The disconnection at the joint 14 can be readily effected by turning the plate 7^a. A circulation can be 90 maintained through the jacket 6 by means of the inlet pipe 15 and outlet pipe 16. 17 is a gas inlet pipe which leads downwardly 95 into the inner vessel 2 and terminates in a jet 18 through which the gas passes into the coil 4. This jet is provided with a downwardly extending aspirator pipe 19 which forms the inlet end of the coil 4. The inner chamber has a gas outlet 20 which connects, by a pipe 21, with a second jet 22, which connects with the coil 5 and which has the aspirator pipe 23. 24 designates a filling connection for the inner vessel and 25 is a gas outlet connection from the outer vessel.

The operation of the apparatus, when 100 used for the determination of benzol in coke oven gas, is as follows:

The valve 9^a is opened, valve 13 is closed

and outlet pipe 25 is opened. Petroleum absorbing oil is poured in through the opening at 24 in sufficient quantity to fill both chambers to a level which is about the top 5 of the coil 4, as indicated in Fig. 2. The filling opening is then closed as is also the valve 9^a. The gas inlet pipe 17 is connected with the gas sampling pipe and the outlet pipe 25 is connected with a suitable gas 10 meter. The gas is turned on and is caused to pass through the apparatus at a definite rate, say approximately 5 cubic feet per hour. The gas first passes through the inlet pipe 17 into the jet 18 from which it bubbles 15 through the coil 4. In passing through this coil it is held in intimate and prolonged contact with the oil therein; and the aspirator action of the jet is such as to continually draw fresh oil in through the aspirator 20 pipe 19. The oil with which the gases come in contact is expelled at the upper end of the coil. The gas then passes through the pipe 21 to the jet 22 and thence into and through coil 5. The fresh oil in this coil effectively removes the last traces of benzol, 25 and the gas finally escapes through the outlet pipe 25 and is measured by the meter. The valves 9^a and 13 may then be opened to simultaneously drain both vessels into a 30 suitable receptacle placed underneath the outlet 12. The valve 13 is then again closed and a little fresh absorbing oil is poured in at 24 and the apparatus shaken so as to rinse both compartments thoroughly. The rinsing oil is drawn off by opening the valve 13. 35 The rinsing may be repeated as often as necessary. The subsequent treatment of the oil consists of distillation, according to well-known practice, forming no part of the present invention.

The arrangement of the two absorbing coils in separate vessels in series enables the gas, after passing through the first coil, to be carried through the second coil having 45 fresh oil therein and which will act to remove the last traces of the absorbable vapors. The concentric arrangement of the two vessels makes the apparatus compact and also enables the use of a common top or cover 50 which facilitates quick opening and cleaning of the apparatus. When the vessels are removed from the jacket, in the manner before described, they can be quickly removed from the cover by taking out the screws 8. The 55 jets 18 and 22 are made detachable so that they may be easily cleaned.

It will be noted that the absorbing coils are each of a length materially greater than the depth of the liquid in which it is immersed. This gives a long confined path for 60 the gases during which they are in intimate contact with the liquid. At the same time, the liquid around the exterior of the coils

is quiescent. This action results in a very complete absorption of the absorbable vapors 65 in the gas.

We claim:

1. Apparatus of the character described, comprising two gas absorbing chambers connected in series, and a gas absorbing coil 70 in each of said chambers, said coils being arranged to be immersed in a liquid in said chambers and having a length greater than the depth of the liquid in which they are contained, substantially as described. 75

2. Apparatus of the character described, comprising two concentrically arranged gas absorbing chambers connected in series, and a gas absorbing coil in each of said chambers, 80 said coils being arranged to be immersed in a liquid in said chambers and having a length greater than the depth of the liquid in which they are contained, substantially as described.

3. Apparatus of the character described, comprising a plurality of chambers connected in series, an absorbing coil in each chamber arranged to be submerged in a liquid therein, said chambers having outlets leading to a common discharge opening, and 90 means for controlling the said opening, substantially as described.

4. Apparatus of the character described, comprising a cover, a support therefor, inner and outer concentric absorbing vessels 95 secured to and suspended from the said cover, and an absorbing coil in each of said vessels, said vessels having a connection whereby the gas after passing through one of the coils may be conducted into the other 100 coil in the other vessel, substantially as described.

5. Apparatus of the character described, comprising a cover, a support therefor, inner and outer concentric absorbing vessels 105 secured to and suspended from the said cover, an absorbing coil in each of said vessels, said vessels having a connection whereby the gas after passing through one of the coils may be conducted into the other coil in the other 110 vessel and having bottom outlets arranged to discharge into a common opening, and valve means for controlling such discharge, substantially as described.

6. Apparatus of the character described, 115 comprising a plurality of absorbing chambers connected in series, and a gas absorbing coil in each of said chambers, said coils forming long, closely confined paths for the gas and absorbing liquid, substantially as 120 described.

In testimony whereof, we have hereunto set our hands.

FREDERICK W. SPERR, JR.
A. ALLISON KOHR.
